UNITED STATES PATENT OFFICE.

BENJAMAN F. MERWIN AND GEORGE W. MERWIN, OF HIGH FALLS, NEW YORK.

SHADE-BRACKET.

1,058,451.

Specification of Letters Patent.

Patented Apr. 8, 1913.

Application filed January 19, 1912. Serial No. 672,075.

To all whom it may concern:

Be it known that we, BENJAMAN F. MERWIN and GEORGE W. MERWIN, citizens of the United States, residing at High Falls, in the 5 county of Ulster and State of New York, have invented new and useful Improvements in Shade-Brackets, of which the following is a specification.

The general object of the invention is to 10 eliminate the employment of screws, tacks, and analogous fastening devices, which are generally used for securing shade brackets to window frames, by providing a shade holder adapted to be readily clamped to the 15 window frame and further adapted not to unnecessarily abrade or mar the same, and still further adapted to engage with the window frame only when in a horizontal position, whereby, the trouble always incident to securing the brackets with screws, 20 the presence of unsightly openings left by screws and the like when the brackets are removed, and the care required to properly align the brackets to prevent sagging of the 25 shade, are all overcome.

Other objects will appear and be better understood from the following description taken in connection with the accompanying drawings, in which,

30 Figure 1 is a front elevation of one embodiment of the invention showing it applied to a window frame. Fig. 2 is a detail plan. Fig. 3 is a rear elevation. Fig. 4 is a vertical cross section. Fig. 5 is an end view. 35 *a* indicates an extensible supporting bar the sections *b* and *c* of which are formed of U-shaped pieces of wire indicated by 5 and 6 and connected at one end as indicated by 7. The sides of the pieces 5 pass through guides 40 8 which are suitably connected to clamp straps 9. The sides of the pieces 6 extend between straps 9 and straps 10 and the said straps 9 and 10 serve to clamp the pieces 6 when drawn together through the coöperation 45 of the bolts and nuts 11. By rendering the supporting bar *a* adjustable or extensible it may be readily adapted to the various widths of window frames.

In order to detachably connect the 50 supporting bar to a window frame such as shown at *d*, we provide a jaw member 12 which is adjustably secured to one of the pieces 6 by means of a rigid cleat 13 and a cleat 14 which is adapted to be secured by 55 means of a bolt and nut 15 so as to coöp-

erate with the jaw member to clamp the piece 5 therebetween. 16 indicate teeth on the jaw member 12 which bite into the side of the frame *d* and are caused to do so by a cam lever 17 moving the jaw 18 into engagement with the opposite side of the frame *d*. The cam lever 17 is pivoted on a plate 19 to which the jaw 18 is slidingly fitted, the plate in turn being connected to the other of the pieces 6 by cleats 20 and 21 one of which 60 coöperates with the plate to clamp the section 6 therebetween when tightened by means of a bolt and nut 22.

The shade brackets 23 and 24 are adapted to receive the opposite ends of the shade 70 roller and are adjustably secured to the pieces 5. In the present instance each shade bracket is shown as having a cleat 26 which extends across the piece 5 and which, when tightened by means of a screw and nut 25, 75 secures the bracket in any of its adjusted positions. Thus, it will be seen that the brackets may be adjusted independently of the supporting bar and the latter may be adjusted independently of the shade brackets, 80 whereby the device may be used with windows and shades regardless of their relative widths.

From the foregoing description, taken in 85 connection with the accompanying drawing, it should be apparent that the supporting bar of my improved shade holder comprises inner and outer parallel members which are held in relatively spaced relation, and each of which comprises sections connected together 90 in a manner to permit the length of the bar to be increased or decreased. It should also be apparent that the means for securing the member sections in adjusted positions secure the members in spaced relation at points 95 intermediate their length, that the means for securing the supporting bar in applied position is carried by the inner member, and that the shade brackets are carried by the outer member.

100 What we claim as new is:

A shade holder, including an adjustable support, comprising a pair of elongated U-shaped sections, clamps for engaging the adjacent legs of the respective sections to secure said sections in adjusted positions, shade brackets adjustably coöperating with the legs of the respective sections, and a window frame engaging member carried by each section, one of said members including a 110

plate fixed to the section, and an offset toothed extension, the other of said members including a strip fixed to the other section, a plate slidably mounted on said strip and 5 having an offset toothed extension, and a lever pivotally mounted on the strip and having a cam portion to engage and operate said movable plate.

In testimony whereof we affix our signatures in presence of two witnesses.

BENJAMAN F. MERWIN.
GEORGE W. MERWIN.
